SUPPORTING STANDARD

George K. Parsons, Detroit, Mich.

Application April 14, 1931, Serial No. 530,116

9 Claims. (Cl. 248—1)

This invention relates to means for mounting dish- and clothes-washing machines, and the like, in a manner enabling their being folded with respect to their support, and has for one of its objects provision of means whereby such a device may be folded beneath a sink or the like when not in use.

Another object of this invention is the provision of such a foldable mounting enabling 10 manual handling and moving of a relatively heavy machine with the expenditure of very little effort.

A further object of this invention lies in the provision of such a foldable mounting which may 15 be quickly and positively locked in the opened position to support the machine as rigidly as if it were carried upon a mounting of conventional construction, and which lock may be quickly and easily released.

20 Other objects and advantages will be apparent from the following description wherein reference is made to the accompanying drawings illustrating a preferred embodiment of my invention, and wherein similar reference numerals designate 25 similar parts throughout the several views.

In the drawings:

Figure 1 is a side elevational view showing an 30 application of my improved foldable mounting to the support of a washing machine, shown carried thereby, the mounting being in opened position and the machine carried thereby ready for use.

Figure 2 is a detail side view, partly in elevation and partly in section, of my improved 35 mounting, the tub supports carried thereby being fragmentarily shown.

Figure 3 is a front elevational view showing a 40 washing machine supported upon my improved standard and partly folded away beneath a sink, also showing in dotted lines the position assumed by the device when fully folded beneath the sink.

Figure 4 is a view showing in top plan the arrangement of Figure 3, also showing in dotted lines the position assumed by the device when 45 folded away beneath the sink, and

Figure 5 is a detail fragmentary sectional view 50 taken substantially on the line 5—5 of Figure 2, and looking in the direction of the arrows.

Referring now to the drawings, reference character 10 indicates a sub-base or support which 55 may be secured to a floor or the like, as by screws 11, and which rigidly supports in vertical position the cylindrical post 12. The post, as shown in Figure 2 may be tubular. Rotatably supported upon the post 12 is a downwardly projecting

sleeve 13 carried by and integral with a housing 14. The housing 14 provides a journal and support for a horizontally disposed tubular shaft 15. For added rigidity a bracing web 16 and a laterally positioned bearing 17 carried thereby 60 in alignment with the bearing 18 formed in the housing, may be provided. The horizontal shaft 15 is preferably rotatable in the bearings 17 and 18. The washing machine tub or other device desired to be carried by the support may be rigidly affixed to the horizontal shaft 15. As here shown, the tub, designated 20, is not directly affixed to the shaft, but to the legs 21, which are in turn secured to the shaft 15 by means of the saddle 22, which may be formed integrally with 65 the legs if desired, and which carries a central sleeve portion 23 through a threaded boss 24 of which a set screw 25 engages to firmly secure the saddle, and consequently the legs and the tub carried thereby, to the shaft 15. It will thus 70 be apparent that the tub may be swung about the axis of the shaft 15 and that the shaft turns with it. The weight of the tub is counter-balanced by a counter-balance spring 26, contained in the housing 14. The inner end of the spring engages 75 a slot 15' in the shaft 15 to constantly urge the tub toward an upright position, and as shown in Figure 5 the outer end is adjustably secured to the side of the housing 14 by means of the clevis pin 14' having a threaded extremity 14² extending 80 through an aperture 14³ in the housing and carrying the nut 14⁴ threaded thereon, by means of which the tension of the spring may be adjusted. A similar but oppositely positioned aperture 114³ is also provided in the housing through 85 which the stem of the pin may pass in like manner when the spring is reversed in position to enable swinging and counterbalancing the machine about the shaft 15 in the opposite direction. Reversing the spring is accomplished by merely removing the pin from the aperture and removing the spring from the shaft, its inner extremity sliding out of the slot, and turning the spring over, placing the stem of the clevis pin through the opposite aperture. The spring will then 90 counterbalance the machine in the opposite direction.

The tube may be maintained upright by the 95 slideable locking pin or detent 28, which is engageable in an aperture 29 in one of the legs 21, as shown in Figure 2. The pin is normally urged into the aperture by the compression spring 30 and may be retracted by the link 31 through the agency of the lever 32, and the operating rod 35. The operating rod is formed with a handle portion 33 100

at its end which projects from the free extremity of the hollow shaft 15, which the rod traverses axially. The lower arm of the lever 32 is bifurcated at its end to engage about the operating rod. The washer-like plate 34 carried by the operating rod enables moving the lever 32 to retract the pin 28 upon pulling the operating rod outwardly by means of the handle 33, as will be apparent upon examination of Figure 2. Bearings and slideways for the operating rod may be provided by a plug 36 inserted in the free end of the hollow shaft 15, and a suitable apertured boss 37 formed in the housing 14, as shown. Adjacent the extremity of the lever 32 the operating rod is formed with a crank portion 38 upon which is fitted a connecting rod in the form of an elongated link 39 which extends downwardly and is connected to, to operate, a pin 40, engageable in a suitable aperture 41 in the sub-base 10 to prevent rotation of the support about its vertical axis. A compression spring 42 may be provided to urge the pin into the aperture; the pin and spring being housed in the radial extension 43 carried by the lower extremity of the sleeve or elongated boss 13. It will thus be seen that by turning the operating rod 35 by means of the handle 33 the pin 40 may be retracted, whereupon the support and the machine carried thereby may freely be swung about the vertical axis furnished by the shaft 12, and that upon turning the operating rod in the opposite direction the pin may again be allowed to enter the same or another aperture in the sub-base to secure the machine in any desired position with respect to said axis, depending upon the arrangement and positioning of the aperture or apertures 41 in the sub-base. It will also be seen that by pulling the operating rod outwardly the machine may be swung about a horizontal axis furnished by the shaft 15 to the position shown in full lines in Figure 3, at which point it is stopped by engagement of the bottom of the saddle 22 with the stop 44, carried by the bracing web 16; or reversely it may be moved from the horizontal position shown in Figure 3 to the upright position shown in Figure 1, where it may be locked by the pin 28 in the manner described.

In order to enable folding the machine in the opposite direction, which is frequently desirable to enable folding it beneath sinks of varying designs, and to still permit the machine to be in the same position when opened for use, I preferably so form the parts carried by the saddle 22 which engage the shaft 15 as to permit reversing the saddle and so the entire machine with respect to the shaft. It will be seen that the sleeve portion 23 is substantially in the center of the saddle, while the two end shaft-engaging portions are substantially alike. This enables reversing the shaft 15, reversing the machine, and replacing the shaft. If the counterbalance spring 26 is then also reversed in the manner previously described, the support will function in precisely the same manner, but will fold in the opposite direction. One of the apertures 29 for the pin 28 is of course placed in each leg, as shown in Figure 2.

Figures 1, 3, and 4 show an application of my support to the mounting of a washing machine or the like so that it may be folded and swung away beneath a sink. The sink, which is somewhat conventionally shown, is designated 45, and Figure 1 shows the machine in the upright position in which it would normally be used. Figure 3 shows in full lines the first step in folding the

machine in one direction, which comprises swinging it about the horizontal shaft 15 to the position there shown. This position is shown in plan view in full lines in Figure 4. The machine may then be swung about its vertical axis upon the shaft 12 to the position shown in dotted lines in Figures 3 and 4, in which it is completely beneath the sink and out of the way. When the counterbalance spring and the machine are reversed in position, the latter of course folds away in the reverse direction, but otherwise in the same manner.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

What I claim is:

1. A supporting standard comprising a vertical shaft, a housing rotatable thereon, a horizontal shaft carried by the housing and rotatable upon its own axis, a support affixed to the horizontal shaft, a counterbalance spring within said housing having one end connected to the horizontal shaft, locking means for preventing rotation of the support about the axis of the vertical shaft, locking means for preventing rotation of the support about the axis of the horizontal shaft, a slideable and rotatable operating rod, a crank carried thereby within said housing for controlling one of said locking means upon rotation of the operating rod, and a lever within said housing and appurtenant said rod for controlling the other locking means upon sliding the rod.

2. A supporting standard comprising a vertical shaft, a horizontal shaft rotatable about the axis of the vertical shaft, a support carried by the horizontal shaft and rotatable about the axes of both shafts, locking means for preventing rotation of the support about the axis of the vertical shaft, locking means for preventing rotation of the support about the axis of the horizontal shaft, and an operating rod slideable to control one of said locking means and rotatable to control the other.

3. A supporting standard comprising a vertical shaft, a housing rotatable thereon, a horizontal shaft carried by the housing and rotatable upon its own axis, a support affixed to the horizontal shaft, a counterbalance spring within said housing having one end connected to the horizontal shaft, locking means for preventing rotation of the support about the axis of the horizontal shaft, locking means for preventing rotation of the support about the axis of the vertical shaft, and an operating rod slideable to control one of said locking means and rotatable to control the other.

4. A supporting standard comprising a vertical shaft, a housing rotatable thereon, a horizontal hollow shaft carried by the housing and rotatable upon its own axis, a support affixed to the horizontal shaft, a counterbalance spring within said housing having one end connected to the horizontal shaft to urge its rotation in one direction, separate locking means for preventing rotation of the support about each shaft, a slideable and rotatable operating rod extending through the hollow horizontal shaft into the housing, and carrying an operating handle, and means within the housing actuatable by the operating rod for controlling one locking means

upon sliding the operating rod and the other upon rotating it.

5. A supporting standard comprising a vertical shaft, a housing rotatable thereon, a hollow horizontal shaft carried by the housing and rotatable upon its own axis, a support affixed to the horizontal shaft, a counterbalance spring within said housing having one end connected to the horizontal shaft to urge its rotation in one direction, separate locking means for preventing rotation of the support about each shaft, a slideable and rotatable operating rod extending through the hollow horizontal shaft into the housing, a crank carried thereby within the housing for controlling one locking means upon rotation of the rod, and a lever within said housing and appurtenant the operating rod for controlling the other locking means upon sliding said rod.

6. A supporting standard comprising a vertical shaft, a housing rotatable thereon, a horizontal shaft carried by the housing and rotatable upon its own axis, a support affixed to the horizontal shaft, a counterbalance spring within said housing having one end connected to the horizontal shaft to urge its rotation in one direction, said support and counterbalance spring being each reversible in position, and means for maintaining the spring under tension in either position, whereby it may be made to urge the horizontal shaft in whichever direction is desired.

7. A washing machine standard comprising a vertical shaft, a housing rotatable thereon, a supporting member carried adjacent and movable with the housing and also rotatable about a substantially horizontal axis, means for lock-

ing the support in desired positions, and a counterbalance spring for urging the support in one direction, said counterbalance spring being reversible in position to enable urging the support in opposite directions thereby.

8. A washing machine standard comprising a vertical shaft, a housing rotatable thereon, a supporting member carried adjacent and movable with the housing and also rotatable about a substantially horizontal axis, means for locking the supporting member in desired positions, and a counterbalance spring for urging the support in one direction, said support being reversible in position, and said counterbalance spring also being reversible to enable urging the support thereby in opposite directions.

9. In combination with a member desired to be supported, a foldable standard for so supporting the same that it may be swung out of the way when not in use, comprising a base, a shaft upstanding therefrom, a frame supported by and swingable about the axis of the shaft, a substantially horizontal shaft journaled in the frame, a housing carried by the frame into which the horizontal shaft extends, means for securing a member desired to be supported to the horizontal shaft, whereby it may be swung with respect to both the horizontal and vertical shafts to move it to desired positions, counterbalancing means within the housing and cooperating with the horizontal shaft to neutralize the weight of the supported object, and means for controlling the swinging movements of the supported object also partially housed within said housing.
